UNITED STATES PATENT OFFICE.

HENRY FORT FLOWERS, OF NEW YORK, N. Y.

DUMPING-CAR.

1,268,830.

Specification of Letters Patent. Patented June 11, 1918.

Application filed November 24, 1915. Serial No. 63,247.

To all whom it may concern:

Be it known that I, HENRY FORT FLOWERS, a citizen of the United States, and a resident of the city of New York, borough 5 of Manhattan, in the county and State of New York, have invented certain new and useful Improvements in Dumping-Cars, of which the following is a specification.

The invention relates to a dumping car 10 having a body which is movable horizontally across the underframe and which can be tilted so as to discharge the load.

One object of the present invention is to construct a car so that it will have a tilting 15 body that will be maintained at a minimum height above the underframe and track and which, at the same time, will be able to deposit its lading when dumped at a point a sufficient distance from a railway track upon 20 which the car is located to enable other cars to subsequently pass along the same track without obstruction.

The invention also involves an operating 25 mechanism for moving the tilting body or dumping body as it may be called to either side of the underframe. According to the specific form of operating mechanism which is herein shown no part thereof projects or extends above or overlies the body. This 30 operating mechanism or body dumping mechanism as it may be called is constructed so that it does not obstruct or deter in any manner the loading of the material on the body and it is also constructed so that there 35 is little likelihood of its becoming damaged or injured during the ordinary use to which cars of this type are subjected.

As showing a specific embodiment of the invention reference is made to the accompanying drawings forming a part of this 40 specification, and in which drawings,

Figure 1 is a plan view of the underframe including the end platforms. In this view there is also shown on one of the end platforms 45 the casing of the dumping mechanism, the casing of the motor which operates the dumping mechanism, the casing of the worm gear reducer between the motor and the dumping mechanism and the casing of the motor controller. In this figure the body of the car has been removed and a portion 50 of the underframe has been broken away.

Fig. 2 is a side elevation of the complete 55 car with the body and underframe partially broken away. In this figure the

body is shown in position on the underframe and a center compartment of the body is the one which has been broken away.

Fig. 3 is an end sectional elevation taken 60 between the diaphragms or sides of the casing of the dumping mechanism, for instance as on the line 3-3 of Fig. 2. In this figure 3 there is indicated the manner in which the dumping mechanism can operate to 65 cause the moving and tilting of the body. There is also indicated in this figure automatic door operating mechanism which causes the side doors to be released as the body is tilted.

Fig. 4 is a sectional plan of an end portion of the car and is a view as taken on the line 4-4 of Fig. 3.

Fig. 5 is a sectional elevation taken as on the line 5-5 of Fig. 4.

Fig. 5^a is a vertical view, partially in section, showing the hitch casting that is carried on the body and a portion of a resisting block that is carried by the casing of the dumping mechanism. The function of the 80 resisting member is to coöperate with the hitch casting in a manner to insure the body being retained in horizontal position on the underframe until the body has been moved from its central or normal position 85 on the underframe.

Fig. 6 is a sectional plan view of Fig. 7 taken as on the line 6-6 of said Fig. 7. In Fig. 6 the controller casing is indicated only by broken lines; this figure in conjunction 90 with Fig. 7 shows the connecting links of the automatic reversing mechanism whereby the controller is actuated when the body approaches its extreme travel to the side of the car. This actuation is accomplished by a 95 hitch casting or a member on the body of the car engaging a link of the automatic reversing mechanism.

Fig. 7 is a partial end elevation of the operating end of the car. This view shows 100 the controller and worm gear reducer whereby the dumping mechanism can be actuated by means of the motor.

Fig. 8 is an end elevation; Fig. 9 is a side elevation and Fig. 10 is a plan of a portion of the hitch casting together with what are known as thimble castings that are located on the hitch casting and portions of the ropes which extend over the thimble castings. There is a hitch casting together 110 with thimble castings and ropes or other flexible connectors at each end of the car.

Figs. 8, 9 and 10 have been provided so as to clearly show the construction which allows the hitch casting to turn during the tilting operation in the thimble castings 5 over which the ropes pass. The thimble castings on each trunnion are separated or parted to allow the tension in the ropes to be equalized without the ropes having to slip in the respective grooves, in the thimble 10 castings, within which the ropes are positioned.

Fig. 11 is a plan view partially in section of an end of the car. The floor-plate on the end of the car has been removed and this 15 figure shows the detail of construction and the manner in which various parts in the underframe are connected.

Figs. 12 and 13 are respectively a side elevational and a vertical sectional elevational 20 view of the underframe. Fig. 13 is a view taken as on the line 13-13 of Fig. 11.

Fig. 14 is an end view of the underframe.

Fig. 15 is a view as taken on the line 15-15 of Fig. 11. In this figure there is 25 shown the track members upon which the rollers that support the body can travel. This is a view showing the construction of what may be referred to as the needle beams in the car underframe.

Fig. 16 is a view taken as on the line 16-16 of Fig. 11 and is a view showing the bolster construction.

The car comprises trucks A, an underframe B, a tilting or dumping body C and 30 mechanism D for effecting the tilting of the body. This last mentioned mechanism will be hereinafter referred to as the operating mechanism or the dumping mechanism since its function is to move the body to one side 40 of the car and dump the load. This mechanism D is actuated by the motor E through a chain F of reducing gears. This chain may be referred to as a worm gear reducer 45 because it comprises worms or screws working in worm gear wheels. The motor is controlled by a controller G which in turn can be automatically moved or actuated by what is known as a hitch casting H. This casting is on the car body and it effects the movement 50 of the controller G through the medium of a reversing or stopping mechanism K when the body has approached its extreme travel to the side of the car. Over this casting or over members located upon it there 55 passes in a manner which will be hereinafter described flexible connectors, to wit, ropes which are actuated from a shaft driven by the motor through the chain of reducing gearing. These ropes and shafts just referred to constitute a part of the dumping 60 mechanism and will be hereinafter described more in detail.

The automatic stopping or reversing mechanism K which actuates the controller 65 comprises horizontally extending links L

and vertically extending links M. The adjacent or inner ends of the horizontally extending links L are connected to a crank N which is on the controller shaft O, while the outer ends of the links L are carried by the vertically extending links M by being pivotally connected to the lower ends of said links M. The links L and M are arranged so that they normally occupy the position indicated by the full lines in Fig. 6 and by the lines 70 made with short dashes in Fig. 7, but they can be displaced by hand in the manner indicated by the lines made with long dashes and dots in Figs. 6 and 7. These links will of course occupy their normal position 75 until the force is applied as by hand to move them to the position where an operating circuit for the motor will be closed, and the links will occupy this last mentioned position until they are restored to their normal 80 position—or even moved to a position where a reverse motor circuit will be closed—by the hitch casting H when the car body has been moved sideways a certain distance from its normal central position.

In Figs. 6 and 7 the hitch casting is indicated by the lines made with dashes and dots and this is the position which the hitch casting occupies when it is about to restore the links L and M of the automatic reversing 95 mechanism K to their normal position or at least when it is about to move the links from the position in which they have been placed by the hand operation of the controller. It will be sufficient to note that when the crank 100 N on the lower end of the shaft O of the controller has been moved to one side or the other that the handle P which is on the same shaft will always be correspondingly moved and thus the position of the controller will always be readily determined by observing the position of the handle P. The movement of the links L and M is sufficient, as previously indicated, to turn the controller shaft O in the proper manner to 110 either shut off the motor or completely reverse the motor according to the conditions desired. It will also be noted that the handle P can be utilized at any time to shut off the motor when desired and that it can also 115 be utilized to open either the forward circuit or the reverse circuit of the motor at all times, except when the car body is at the extreme travel to one side or the other of the car in which case the controller handle 120 can be positioned only in the proper direction to open a reverse circuit so as to start to move the body toward its normal central position.

The underframe comprises two center sills 125 1 and 2 and two longitudinally extending side sills 3 and 4, the latter of which are positioned adjacent to or over side bearings 5 and 6, respectively, which are on the trucks. The ends of these several sills are 130

connected to what may be referred to as curved end sills 7, one at each end of the car.

Fig. 16 illustrates what may be referred to as the bolster construction and this figure shows how the center and side sills are built into the bolster. This bolster has side bearing plates or members 21 and 22 arranged over the side bearings 5 and 6 on the truck. There are also comprised in the underframe transverse members or needle beams, such as shown in Fig. 15, and on the tops of these transverse members there are provided tracks 8 having upstanding projections, rivet heads or teeth 9. This Fig. 15 shows how the center and side sills are built in the transverse members. Upon each of these tracks rollers 10 and 11 rest and these rollers are cut out or notched at 10^a and 11^a so that they will in fact operate as gears as they roll along and mesh with the projections 9 on the track. These rollers are connected by links 23 whereby they will operate in pairs and there extends from the center of each of these rollers what may be considered as a projecting shaft. These projecting shafts are designated by the reference character 24 and they are constructed so that they can be engaged by roller stop castings 25 which are secured to the body. These stop castings engage the projecting shafts as the body approaches the end of its horizontal movement toward the side of the car. The parts 26 on the stop roller castings are the parts which engage the projecting shafts 24 on the rollers and these stop castings are provided to limit the horizontal movement of the body toward the side of the car and to hold the body in a definite position relative to the rollers whereby during the tilting movement of the body it and the roller will swing together upon tracks 8 with the rollers operating as rockers. The car body is shaped so as to receive these rollers and in fact in the central portions of the car there are provided transversely extending pockets, as at 27' (see Fig. 2). It will be noted that, in order that the car body shall have the movement above described, it is necessary the body be provided with track members 27 which rest upon the rollers. These track members each have a series of transversely extending depending rivet heads that provide teeth or projections 28 which mesh with or fit into the notches 10^a and 11^a in the rollers. It will thus be manifest that with the toothed construction on both the body and the underframe tracks the car will always be maintained in a proper position relative to the underframe as the body moves on the rollers transversely of the underframe and as the rollers move transversely of and on the underframe. In other words, the body cannot become cramped or displaced due to a slipping of

the body on the rollers, or due to a slipping of the rollers on the underframe.

The car shown in the drawings in this application is an improvement upon the car shown in the drawings of an application filed by me in the United States Patent Office on November 27th, 1914, to wit, Application Serial No. 874,165. In said application an operating shaft of the dumping mechanism extends from one end of the car body to the other and is located over the car body.

According to the form of car shown in the present application a construction has been provided wherein the operating shaft is located below the body instead of above it. The shaft just referred to is designated by the reference character 12. This shaft is located in the space between the center sills 1 and 2 and it is operated as previously indicated by the motor E through the worm gear reducer F. This worm gear reducer comprises a worm or screw 29 which is driven by the motor E, a worm wheel 30 driven by the worm 29, a worm 29' connected to and driven by worm wheel 30, and a worm wheel 30' which is driven by the worm 29'. The worm wheel 30' is the member that is connected to and that drives the operating shaft 12. This shaft extends the full length of the body and a distance beyond it and there are provided at each end of the shaft winding drums 13 over which the ropes or flexible connectors 15 and 16 pass or about which they are wound.

From an inspection of Fig. 3 it will be observed that the flexible connector 15 passes over and in engagement with the thimble casting 17 and is in effect secured or hitched to the hitch casting. From the thimble castings the two parts 15^a and 15^b of the rope pass over an idler wheel or sheaves 18, and finally both of these parts pass over and in engagement with the winding drum 13. Similarly the rope or flexible connector 16 passes over the thimble casting 19 and is thus in effect secured or hitched to the hitch casting upon which the thimble castings are located. Each part of the rope, to wit, 16^a and 16^b passes over an idler wheel 20. Finally both of these parts pass over and in engagement with the winding drum 13. While the ropes 15 and 16 have been described as being two different members still they may, as a matter of fact, constitute two parts of the same rope and which parts may be considered to be connected.

From an inspection of this figure it will also be observed that the hitch casting is so arranged that when the stop roller castings 25 strike the projecting shafts on the rollers the center of the hitch casting will substantially coincide with the pitch line of the rollers. In order to take up any slack in the ropes or flexible connectors there is pro-

vided a tightening sheave 32 carried in a yoke 33, the latter of which is held in retracted position by a compression spring 34. A nut 35 is on the threaded stem end of the yoke and serves as a means for regulating the force which the spring 34 exerts upon the yoke and consequently the force which the tightening sheave exerts upon the ropes.

From an inspection of Fig. 3 it will be observed that this spring forces the sheave 32 downwardly against the two portions of the rope 16 and thus maintains taut the entire set of flexible connectors which extends around the hitch castings over the idler 15 sheaves or wheels 18 and 20 to the winding drum or drums 13. The center of gravity of the car body and the parts movable therewith is approximately at the point marked C. S. It has been previously pointed out 20 that the body moves transversely of the underframe as the body moves on the rollers and as the rollers in turn travel along the tracks on the underframe. This movement continues until the stop members on 25 the body engage the projecting shafts 24 on the rollers. From then on the further movement of the body tends to take place with the rollers acting as rockers. As, however, the motor has been stopped before the 30 body assumes its full tilted position the set of flexible connectors 16^a and 16^b which are then held—supposing for example the car body to have been moved to the right of the underframe—restrain the further outward 35 movement of the hitch casting that is secured to the car body. The center of gravity of the car body is now to the right of the vertical plane passing through the centers of the right hand rollers and hence the 40 body tends to continue to assume a farther tilted position. As the body, however, is restrained from moving outwardly, due to this restrained effect on the part of the flexible connectors or ropes 16^a and 16^b, the 45 body will not move farther on the rollers as rockers, but it will tend to swing on the upper portion of the rollers. This swinging about the upper portion of the rockers causes the center of gravity of the body to 50 be lifted, so to speak, and causes the rollers to be forced to the left a short distance dependent upon the amount of further movement of the body toward full tilted position. The raising of the center of gravity of the 55 body during this continued movement has the effect of absorbing the momentum or energy which the body and its contained load had acquired during the first portion of the tilting operation and hence the body 60 comes to the end of its full tilted position very gradually and it has at the end of this period only a small amount, if any, of accumulated energy, the greater part of the energy having been absorbed by the energy 65 itself raising the center of gravity of the

body in the latter part of the tilting operation. It will be observed that the flexible connectors which pass over the thimble castings that are on the hitch casting at each end of the car are in effect secured to the car body at each end of the latter. The hitch castings and the flexible connectors are positioned so that the line of force—which may be referred to as a restraining force—restrains the body from substantial outward movement during the last portion of the tilting operation. Not only the body is restrained from this further outward movement but also the rollers about which the body previously swung as rockers. This line of force is located above the center of the rollers, which acted as rockers, thus being located in an advantageous position to accomplish this restraining operation. The tracks of the car body are, of course, above the center of the rollers and the continued angular movement of the car body, without a continued outward movement of the car body, will result in the lifting of the center of gravity, or will at least prevent the lowering of the center of gravity of the car body, or the center of gravity of the combined body and load, if a load is in the body. The door gear mechanism or the door latch gear mechanism as it may be called is substantially the same as the corresponding mechanism which is clearly and fully described in the application Serial No. 874,165 above referred to. In the pending application just referred to there is found what is designated as a shaft operating handle 40, a stop or locking bolt H which is located on the underframe, a slotted lever 38 and a bell-crank lever 37. The corresponding parts in this application are designated by the reference characters 40, 41, 38 and 37. In other words, these four parts bear the same reference characters in both applications with the exception of the stop or bolt which in the pending application is designated by the reference character H and in the present application by 41. The stop 41 is a movable stop (see Figs. 3, 4 and 5) and can be positioned by a handle 42 that extends upwardly through the floor plate of the end platform. This plate has a transversely extending slotted portion 43, a longitudinally extending slotted portion 44 and a transversely extending slotted portion 45, and the bolt 41 can be moved from out of the path of the lever 38 by withdrawing the handle 42 from the slotted portion 43, moving the latter along the slotted portion 44 and placing the handle in the slotted portion 45, the latter of which will serve to hold the bolt 41 in its inoperative position. There is also shown attached to the end of the car a spring 46 which can be utilized to engage the handle 40 and retain it in any desired position.

An inspection of Figs. 11, 12 and 13 will make it clear that the center and side sills 2 and 4 are connected to the curved end sills 7 by means of the angle irons 50, 51 and 52. To the underside of the end sill 7 there is secured what may be referred to as the apron 53. This apron is in fact a curved channel member which may be considered as a depending portion of the end sill. To the underside of the ends of the center sills there is also secured channel members 54. A bar 55 is located at each end of the car and extends the full width thereof. This bar is secured in any suitable manner, as at 56 and 15 57 respectively, to the ends of the depending curved member 53 and to the underside of the members 54. To this transversely extending bar 55 and the underside of the members 54 there is secured a curved member or plate, so to speak, 58. The function of this curved plate 58 is to serve as a support for the free end of a swinging yoke or connecting link, the fixed end of which link is carried in the member 59. Very frequently with cars of the class described it is found advisable to force the car along the track even while the body is in its tilted position. This of course brings more or less of a strain where the body is supported on the underframe, especially if the lower portions of the body or the swinging doors are in engagement with the lading which has been dumped.

In order to take care of the thrust which is transmitted from the body to the underframe at this time there are provided gusset plates or brace members 60 at each end of the car. These gusset plates or members are located over the side sills and extend to the upper portion of the transverse diaphragms or casing members of the dumping or operating mechanism D. The construction just referred to is shown in Figs. 2, 4, 5 and 5^a and from these figures it will be clear that any blow due to the longitudinal movement of the body relative to the underframe is transmitted first to the depending flange of the angle iron 61 through the plate 62 of the dumping or operating mechanism D, the gusset plates or braces 60, the end or platform floor plates which are on the sills and finally to the side sills themselves.

In order that the body may be prevented from raising relative to the underframe 55 when the body is in the central position on the underframe there is provided a block or resisting member 63 which is secured near the central portion of the angle iron 61. This block or resisting member is clearly shown in Figs. 3 and 5^a.

In regard to the dumping features of this car, it will be observed the car is constructed so that the kinetic energy acquired by the body—and also by such of its load as is retained—during the first portion of its tilting

operation is converted into potential energy as the kinetic energy is employed to effect a raising of the center of gravity of the car body and a corresponding raising of such of the load as is retained therein.

The improvements herein set forth are not limited to the precise construction and arrangement shown and described, for they may be embodied in various forms and modifications without departing from the spirit 75 and scope of the invention.

What I claim is:

1. A car of the class described comprising in combination an underframe having transversely extending tracks thereupon, pairs of rollers mounted upon each of said tracks, a car body mounted upon said rollers and arranged so that it can be moved horizontally transversely of the underframe and then moved to inclined position, car dumping 85 mechanism comprising a shaft which is located below and extending the full length of the body, and means between the shaft and the body whereby as the shaft is rotated the body will be forced horizontally to a position 90 where it can be tilted.

2. In a car of the class described the combination of an underframe having transversely extending tracks, pairs of rollers mounted upon said tracks, a car body mounted upon said rollers, an operating shaft located below the car body and extending the full length thereof, and flexible connectors at each end of the car body, each of which connectors extends from said shaft over 100 idler wheels or sheaves carried on the underframe to members which are secured on the body.

3. A car of the class described comprising in combination an underframe having 105 spaced center sills, transversely extending tracks on the upper side of the underframe, rollers mounted upon said tracks, a car body mounted upon said rollers, and a dumping mechanism comprising a shaft which is located between said center sills, hitch members or castings which are secured to the body, one at each end, flexible connectors hitched to said hitch members or castings and extending to winding drums on said 110 shaft, which flexible connectors pass over idler wheels that are carried on the underframe, the construction and arrangement of the various parts being such that as said shaft is rotated the body will be forced 115 transversely of the underframe to a position where it can be tilted.

4. In combination in a car of the class described an underframe having transversely extending tracks, a pair of rollers 125 on each track and movable along the latter, a body mounted on said pairs of rollers so that it can be moved transversely of the underframe and relatively to said pairs of rollers to a side tilting position, and dump- 130

ing mechanism said dumping mechanism comprising a shaft which is located below the body, flexible connectors secured or hitched to the body and idler-wheels over which said connectors pass, the construction being such that by rotating the shaft the body will be forced sidewise from a central to a side tilting position.

5. A dumping mechanism for cars comprising an operating shaft, a hitch casting which is secured to a car body, a pair of thimble castings upon each hitch casting, a flexible connector which passes over one of said thimble castings, thence over an idler 70 wheel at the right hand side of the car, thence back to a winding drum on the operating shaft; a flexible connector which passes over the other thimble casting, thence over an idler wheel at the left hand side of 75 the car, and finally to a winding drum on the shaft.

6. In a car of the class described the combination of an underframe having transversely extending tracks thereupon, pairs of 80 rollers mounted upon said tracks, a car body mounted upon said rollers and having track members whereby the body can roll along said rollers, stop roller castings on the body arranged to engage parts of the pairs of 85 rollers, and means for forcing the body horizontally to a position where the stop roller castings engage projecting portions on the rollers whereby the body can be moved from a horizontal to a tilting position, the underframe comprising in combination a pair of center sills extending the full length of the 90 car, a pair of side sills extending the full length of the car, a curved end sill to which all of the sills are connected, and a depending apron in the form of a channel secured to said end sill, there also being secured to the underside of the center sills and the side sills, members to which a curved supporting 95 plate is secured whereby a support can be provided for the swinging tongue or draw-bar.

7. In a car of the class described the combination of an underframe having transversely extending tracks, pairs of rollers 100 mounted upon said tracks, a car body mounted upon said rollers and having track members whereby the body can roll along said rollers, stop roller castings on the body arranged to engage the parts of the pairs of 105 rollers, and means for forcing the body horizontally to a position where the stop roller castings will engage the said pairs of rollers whereby the body can be moved from a horizontal position to a tilted position; said 110 means comprising a shaft which is located below the body, a motor, a worm gear reducing gearing between the motor and the shaft whereby the shaft can be driven from the motor, and a set of two flexible connectors hitched or secured to the body at

each end thereof, one flexible connector of each set passing from the body over an idler wheel or sheave which is located at the right hand side of the car to a winding drum on said shaft, the other flexible connector of each set passing over an idler wheel or sheave which is located at the left hand side of the car to a winding drum on 115 said shaft.

8. In a car of the class described the combination of an underframe, a body mounted thereupon so as to move transversely thereof, an operating shaft located below the body, a motor, a reducing gearing between the motor and the shaft, and a pair of flexible 120 connectors extending from the body, one passing over an idler wheel carried by the underframe at one side of the car and the other flexible connector passing over another idler wheel carried by the underframe at the 125 other side of the car, both of said connectors passing from the idler wheels over to a winding drum on the shaft.

9. A car of the class described having in combination an underframe, a shaft carried 130 by the underframe, a motor for operating said shaft, a pair of flexible connectors, one of which connectors is secured or hitched to the body and passes over an idler wheel or sheave which is carried on the underframe to a winding drum on the shaft, the other of which flexible connectors is secured or hitched to the body and passes over a second idler wheel or sheave which is carried on the underframe to a winding drum on 140 the shaft.

10. In a car of the class described the combination of an underframe and operating shaft carried by the underframe, a motor for driving said shaft, and a motor controller carried by the underframe, means between the shaft and the car body whereby the car body can be moved by the turning of said shaft when the motor is actuated, there being located between the body and 145 the controller an automatic stopping mechanism whereby the controller will be positioned by the car body when the latter moves a certain distance.

11. A car of the class described comprising in combination an underframe, a body carried on the underframe, a motor on the underframe for moving the body laterally relative to the underframe, a stopping mechanism on the underframe which stopping mechanism is actuated by a member on the body as the latter reaches the extremity of its sidewise or lateral travel, such stopping mechanism being associated with the controller so that when the controller is moved 150 to open or start the motor for the purpose of moving the car body laterally from its central position the stopping mechanism will be positioned, and so that when the stopping mechanism is actuated as the car body 155

reaches the extremity of said sidewise or lateral travel said stopping mechanism will move the controller to shut off the motor.

12. A car of the class described comprising in combination an underframe, a car body mounted on said underframe so that it can be moved laterally or transversely relative thereto, a reversible motor on the underframe for moving the car body in reverse direction transversely relative to the underframe, a controller for the motor, and a reversing mechanism on the car body, which reversing mechanism is actuated by the member on the car body as the latter reaches the extremity of its transverse sidewise movement, said reversing mechanism being associated with the controller so that when the controller is moved to open or start the motor in order to move the car body in one direction from its central normal position on the underframe at one side thereof the reverse mechanism will be positioned, and so that when the reversing mechanism is actuated by a member on the car body as the body reaches the extremity of its sidewise or transverse movement said reversing mechanism will position the controller so as to reverse the motor.

13. A car of the class described comprising in combination an underframe, a body mounted so as to move transversely relatively thereto, a motor and mechanism actuated thereby for moving the body in the manner indicated, a controller for the motor, a pair of horizontally extending links connected at their adjacent ends to the movable element of the controller, a pair of vertically extending links to which the outer ends of the horizontally extending links are pivotally connected, and a member on the body arranged to engage one of said vertically extending links so as to position the movable element of the controller when the body has moved a certain distance relative to the underframe.

14. A car of the class described comprising in combination in the underframe there-of a pair of center sills, a pair of side sills, all of which sills are connected to a curved end sill, said end sill and said center sills having secured thereto depending members; a transversely extending bar secured to the ends of the depending member on the end sill and to the depending members on the center sills, and a curved plate or member secured to the transversely extending bar and to the depending members on the center sills.

15. A car of the class described comprising in combination an underframe, a body mounted upon the underframe so that it can be tilted relatively thereto, and means between the underframe and the tilting body for causing the body to move relatively to the underframe, said means comprising a

motor, a shaft, and a worm gear reducer between the motor and shaft, the parts being constructed and arranged so that when the motor operates it can move the body relatively to the underframe through the medium of said worm gear reducer and shaft.

16. A car of the class described comprising in combination an underframe, a body mounted on the underframe so that it can be moved transversely of the underframe, a longitudinally extending shaft carried by the underframe, a motor carried on the underframe, a worm gear reducer located between the shaft and the motor whereby power from the motor will be transmitted to the shaft, and means between the shaft and the body whereby as the shaft turns the body will be caused to move transversely of the underframe.

17. A car of the class described comprising in combination an underframe, a body mounted upon the underframe so as to move transversely relative thereto, flexible connectors connected or hitched to the body, passing over idlers at the sides of the car and thence to winding drums on the underframe, and means on the underframe that engage said flexible connectors so as to maintain them taut.

18. A car of the class described having in combination an underframe, a car body mounted on the underframe so as to move transversely relative thereto, flexible ropes connected or hitched to the body, passing over idler or sheave wheels at the right and left hand of the car and thence over winding drums located at the central portion of the car, and a tensioning device having spring means for maintaining the flexible connectors taut.

19. A car of the class described comprising in combination an underframe having transversely extending tracks, pairs of rollers mounted upon said tracks, a car body having transversely extending tracks which rest upon said rollers, stop members carried by said body and arranged to engage said rollers when the car body has been moved the desired distance relative to the underframe, and means comprising flexible connectors which pass over wheels that are on the underframe and are secured to the car body whereby after the car body is swung for a limited distance on a part of the rollers as rockers further movement of the car body outwardly will be restrained by the flexible connectors, the arrangement of the parts and the construction being such that with a further tilting of the car body the center of gravity of the car body will be raised due to the car body swinging on and relative to rollers with which it has previously swung as rockers.

20. A car of the class described comprising in combination an underframe, a body

mounted upon the underframe so that it can be tilted relatively thereto, a casting on the car body, a transversely extending member carried on the underframe with which the ends of said casting will engage when the car body moves longitudinally relative to the underframe when the body is in its normal position relative to the underframe, and gusset plates or braces for bracing the transverse member when thus engaged by said casting.

21. A car of the class described comprising in combination an underframe having side sills, a tilting car body mounted upon the underframe so that it can move transversely relative to the underframe, a hitch casting at each end of the car body, transversely extending members carried by the underframe and arranged to be engaged by said hitch castings when the car body moves longitudinally relative to the underframe, and gusset plates or braces extending from the side sills of the underframe to said transversely extending members.

22. A car of the class described having in combination an underframe, a car body mounted on the underframe so as to move transversely relative thereto, a hitch casting carried by the car body at each end thereof and a transversely extending member located at each end of the car body and carried by the underframe, which transversely extending members are provided with resistance blocks located above and adjacent to the hitch castings when the car body is in its central position.

23. A dumping car of the class described comprising in combination an underframe having horizontally and transversely extending tracks, a pair of rollers mounted upon and movable along each of said tracks, a body mounted upon said rollers so as to roll along the same in a direction transverse to the underframe, and means for moving the body in such transverse direction to a position where the body can be swung from a horizontal to a full tilted position, the center of gravity of the car body and the load contained therein being so positioned, the body being mounted upon the underframe in such a manner, and the body moving means being so constructed and arranged that during the first portion of the tilting movement the body will swing about or on a part of said rollers as rockers whereby said center of gravity will fall, and so that during the latter part of the movement of tilting the car body and the rollers as rockers will be restrained whereby the further movement of the body will raise the center of

gravity and there will be converted into potential energy the kinetic energy acquired during the first portion of the tilting movement of the car body.

24. A dumping car having an underframe, a tilting body supported upon notched rollers that move transversely relative to the underframe, and operating mechanism for moving the body transversely relative to the underframe and constructed so as to restrain the body against outward movement when the body is at or near the extremity of its sidewise or outward travel, the body having teeth or projections that engage the notches of the rollers and being controlled by said operating mechanism in such a manner that kinetic energy acquired by the body during the first portion of the tilting movement is converted into potential energy during the last portion of the movement of the body to full tilted position.

25. A dumping car of the class described comprising in combination an underframe having horizontally and transversely extending tracks, a pair of rollers mounted upon and movable along each of said tracks, a body mounted upon said rollers so as to roll along the same in a direction transverse to the underframe, and operating mechanism for moving the body in said transverse direction to a position where the body can be swung from a horizontal to a full tilting position, the center of gravity of the car and the load contained therein being so positioned, the body being mounted upon the underframe in such a manner, and the operating mechanism being constructed and arranged so that during the first portion of the tilting movement the body will swing about a part of said rollers as rockers, and so that during the last part of the movement of the car body toward full tilting position further outward movement of the car body and of the rollers will be restrained in such a manner that the continued angular movement of the car body will be such that the car body will roll on the rollers which served as rockers in a manner to prevent a falling of the center of gravity of the car body and its load whereby there will be a converting into potential energy during the latter part of the tilting movement of kinetic energy acquired during the previous portion of the movement of the car body.

This specification signed and witnessed this 23d day of November, A. D., 1915.
